STEAM GENERATING APPARATUS

Karl Baumann, Urmston, England

Application October 18, 1930, Serial No. 489,658
and in Great Britain November 15, 1929

3 Claims. (Cl. 122—33)

This invention relates to steam generating apparatus and concerns more particularly a tubular boiler of the kind in which use is made of a heat carrier, such as water under very high pressure or mercury, for the purpose of transferring heat from the furnace to the water from which the steam is to be generated.

According to the invention a steam generator of the kind referred to comprises a substantially rectangular furnace chamber the walls of which are lined with water tubes, said chamber having an extension through which the furnace gases leaving the chamber pass, and having disposed in said extension, exposed to said furnace gases, but substantially protected from the direct heat of the flame in the furnace chamber, a tube system constituting the heating portion of a closed circuit for the heat carrier, which circuit includes the heating tubes of an evaporator for the generation of steam. The steam generated in the evaporator preferably mixes with the steam generated in the water walls of the furnace chamber and is passed through a superheater disposed in the said furnace extension before being used for power generation or other purposes.

The invention is illustrated by way of example in Figs. 1, 2 and 3 of the accompanying drawings, which show diagrammatically two preferred forms of steam generating apparatus according to the invention.

Referring to the drawings, 1 is the furnace which may be adapted to be stoker fired or fired with pulverulent or liquid fuel, and is enclosed by walls constituted of water tubes 2. These water tubes 2 are extended to line the extension of the furnace chamber and are connected to a suitable steam and water drum 3, hereinafter termed the main drum. Downcomers 2a pass externally from the main drum 3 to lower headers 4 at the bottom of the water walls to ensure proper circulation therethrough. The water tubes 2 forming the back of the furnace, are bent at the upper part of the furnace chamber as shown at 5 to restrict somewhat the passage by which the furnace gases leave the chamber 1, the extension 6 of the chamber 1 taking the form of a substantially horizontal flue. The bent form of the water walls also serves to provide a screen for the tubes of the heat carrier 7 which tubes are arranged so as to be heated by the furnace gases immediately upon their entry into the said extension.

The heat carrier 7 comprises a heating element 8 disposed in an auxiliary drum 9 the

steam from which drum is led to a junction 10 from whence it is passed, together with the steam from the main drum 3, through one or more superheater elements 11. These superheater elements are preferably disposed to be 60 heated by the furnace gases after passing some or all of the tubes of the heating system of the heat carrier 7. In Fig. 1 the superheater is disposed wholly beyond the heating tubes of the heat carrier 7 and is arranged so that the steam 65 traverses the first portion of the superheater in the same general direction as the furnace gases, and the latter part of the superheater in counter-current to the furnace gases. In the constructions shown in Figs. 2 and 3 the super- 70 heater element 11 is disposed between two portions 7 and 7' of the heat carrier.

As shown, the main drum 3 is disposed adjacent the end of the extension 6 where the furnace gases leave, and the leaving gases prefer- 75 ably pass in direct contact with the water tubes. All other portions of the water tubes may be protected against direct exposure to the furnace gases by a covering of refractory or other material as shown by the cross-hatching. In suitable circumstances however such covering may be dispensed with. The gases may finally pass to an economizer and air preheater as is usual.

A steam generator constructed as described above will possess various advantages over 85 known constructions of generators of the kind referred to. The number of water tubes is reduced to the minimum required for lining the furnace walls, while the heating tube system of the heat carrier is exposed to a moderate heat 90 only. It will be understood that the heat carrier is preferably evaporated in the heating tube system and recondensed upon giving up heat in the tubes of the evaporator, from which it flows back to the heating tube system. The 95 latter moreover comprises tubes of relatively small diameter and, as well as the superheater, may be readily arranged in any manner that may be convenient.

In Figure 3 two superheaters are shown as 100 connected alternately in series with the heating tubes 8 and 8', respectively, of two evaporators 9 and 9', as for example, in accordance with proposals made in my copending application for Letters Patent Serial No. 473,695. It will readily be appreciated that, instead of providing the second evaporator 9', the heating tubes 8' may be disposed within the steam and water drum 3 in which case the steam and water drum would 105 act as an evaporator.

It will be obvious that many other modifications may be embodied in the apparatus without departing from the scope of the invention. In all cases a particularly compact construction 5 of steam generator is afforded, and it will be observed that the drums employed may be of relatively small diameter, which is particularly advantageous when steam generation at high temperatures and pressure is in question.

10 I claim:

1. In a steam generating plant a substantially rectangular furnace chamber, said furnace chamber having an extension through which the furnace gases leaving the chamber pass, a tube 15 system disposed in said extension and constituting the heating portion of a closed circuit for a heat carrier which circuit includes the heating tubes of an evaporator for the generation of steam, and a superheater disposed in the said 20 furnace chamber extension through which the steam generated in the walls of the furnace chamber and in the evaporator is passed before being used.
2. In a steam generating plant a substantially 25 rectangular furnace chamber the walls of which are lined with water tubes discharging at their upper ends into a steam and water drum and connected at their lower ends by downcomers from said drum, said furnace chamber having an extension through which the furnace gases 30 leaving the chamber pass a tube system dis-

posed in said extension and containing a heat carrier said tube system comprising two coils spaced apart and constituting the heating portion of a closed circuit which includes the heating tubes of an evaporator for the generation of steam, and a superheater disposed between said coils of the tube system in the furnace chamber extension and connected at one end thereof to the steam outlet of the evaporator.

3. A steam generating plant comprising a substantially rectangular furnace chamber the walls of which are lined with water tubes discharging at their upper ends into a steam and water drum and connected at their lower ends by downcomers from said drum, said furnace chamber having an extension through which the furnace gases leaving the chamber pass and the walls of which are lined with water tubes comprising prolongations of the furnace wall tubes, a tube system disposed in said extension and containing a heat carrier, said tube system comprising two coils spaced apart and constituting the heating portion of a closed circuit which includes the heating tubes of an evaporator for the generation of steam and a superheater disposed between said coils of the tube system in the furnace chamber extension and connected at one end thereof to the steam outlet of the evaporator and also the steam outlet of a drum disposed in the water tube circuit.
